UNITED STATES PATENT OFFICE.

WALTER M. SULLIVAN, DECEASED, LATE OF NEWARK, NEW JERSEY; BY HARRIET S. SULLIVAN, NOW BY MARRIAGE HARRIET S. PAYNE, ADMINISTRATRIX, OF NEWARK, NEW JERSEY.

SPARK-GAP STABILIZER.

Application filed January 26, 1921. Serial No. 440,146.

This invention relates to spark stabilizers and is particularly directed to spark gap stabilizers.

An object of this invention is to provide improved sonority for spark gap means, particularly for use in radio transmission, and for increasing generally the efficiency of damped oscillation transmitting sets. In the more preferred forms of the invention, 5 such improvements are effected by spark gap stabilizing means comprising an electrically conducting electrode located in suitable relation to the rotary electrode and the stationary electrode.

10 In carrying out the invention, preferably rotary electrodes of uniformly distributed sparking points are employed.

Further features and objects of the invention will be more fully understood from the 15 following description and the accompanying drawings, in which—

Fig. 1 is a diagrammatic view of a transmission circuit embodying the invention;

20 Figs. 2 and 3 are respectively detail side 25 and end elevations on an enlarged scale, showing an eight toothed rotary electrode and a stationary electrode and a spark gap stabilizer in accordance with this invention;

Figs. 4 and 5 are respectively an end elevation of one form of specific embodiment 30 of spark gap stabilizer and a detail elevation of an eight toothed rotary member.

35 Referring to Fig. 1, the transmitting circuit illustrated comprises a suitable alternator 1 whose alternating current winding 2 is connected at its terminal 3 to the conductor 4 and its opposite terminal 5 connected to the conductor 6. The direct current field winding 7 is connected at one end 40 of the lead 8 connected to a brush 9 of rotor 10, the other brush 11 being connected by the lead 12 at 13 to the conductor 6. The opposite end of the field winding 7 is connected by the conductor 14 to the terminal 15 of the distributing block 16. The terminal 15 is connected to the terminal 17 of the distributing block 16, thence to the lead 18 connecting with the terminal 19 of the distributing block 16, thence to the terminal 20 of the distributing block 16, thence by the lead 21 to the contact 22 of the field switch 23. The conductor 6 is connected to the terminals 24 and 25 of the distributing block 16 and thence by the lead 26 to the movable contact arm 27 of the field switch 23. The contact 28 of the field switch 23 is connected by the lead 29 to the dry cell 30 and thence through the conductor 31 to the terminal 17 of the distributing block.

55 The keys 32, 33, 34 are respectively connected in parallel and the respective pairs of contacts 35, 36, and 37, 38 and 39, 40, which key circuits are preferably provided with the winkerlights 41, 42, 43, respectively, to indicate to the pilot or observer the 60 transmission of the transmitted message. The detail construction of the distributing block, its terminals and connections are of 65 any approved form.

The circuit of the alternator is completed 70 on one side through the conductor 6, terminal 24, thence through any key 32, 33, 34, thence through the common return conductor 44 to a terminal 45 of the primary 46 of the transformer 47. The opposite terminal 48 of the primary coil 46 is connected to the conductor 4.

75 Secondary coil 49 of the induction coil 47 is connected at its terminal 50 to the conductor 51, thence at 52 to the lead 53 and 80 the stationary spark electrode 54. The conductor 51 extends to the adjustable contact arm 44 of the inductance 56. The opposite terminal 57 of the secondary coil 49 is connected by the conductor 58 to the opposite 85 terminal 59 to the primary inductance 56, of the oscillation transformer 56.

90 The rotary spark electrode 60 is disposed in suitable sparking relation with the fixed electrode 54 and rotated by suitable rotating means including a shaft 61 which may be grounded, as by means of the ground wire 62 leading to the ground 63. The primary inductance 56 is connected at its terminal 59 by the lead 64 and to the terminal 65 of the 95 secondary inductance 66, whose movable contact 67 is connected through the hot wire ammeter 68 to the terminal 69 of the variometer 70, whose outer terminal 71 is connected by the lead 72 to the antenna 73. The lead 64 is preferably connected by the conductor 75 to the ground 63. The arm 70a of the variometer 70 is connected at a 100 suitable point 75 to the conductor 72.

For air plane use of the invention, the shaft 61 of the movable electrode 60 and the conductor 64 of the oscillation transformer 56^a may be connected to any suitable counterpoise 63. In such air work, the antenna is of the flying type, as indicated, the effective length of which is controlled by means of the reel 76 and fairlead 77, as will be understood.

10 It will be understood that the number of teeth on the rotary electrode disk 60 is selected for the desired tone of the signals, the installation of the proper electrode being made in airwork prior to the airplane's leaving the grounds. The variation of inductance of the sending circuit while in the air, is effected by means of the variometer, for the purpose of tuning the antenna circuit to the wave of the closed oscillating circuit, as 15 indicated.

20 Coacting with the stationary electrode 54 and the rotary electrode 60 there is provided, in accordance with this invention, spark gap stabilizer means shown as a metallic electrode 80, shown diagrammatical in Fig. 1, which may be grounded or counterpoised or 25 not grounded or counterpoised.

25 In Figs. 2 and 3, there is shown on a somewhat enlarged scale, the rotary electrode 60, 30 the stationary electrode 54 and a preferred form of stabilizer electrode 80 disposed at one side of the rotary electrode 60 and closely adjacent the fixed electrode 54. In these 35 figures, the stabilizer electrode 80 is shown connected by the conductor 81 to ground or counterpoise 63.

40 From discoveries made in the use of this invention, an effective distance of the stabilizer electrode 80 from the path of the 45 spark is within the range of one eighth inch to one fourth inch for synchronous rotary spark transmission sets yielding spark tones from 450 to 1800 sparks per second, depending upon the speed of rotation of the rotary electrode 60 in synchronism with the rotor 10 of the alternator 1.

50 The particular rotary electrode 60 shown in Figs. 2 and 3, is provided with eight teeth yielding approximately 600 sparks per second.

55 By means of this invention, the stationary electrode may remain in any set position, and need not be adjusted to different positions, as is normally required when substituting rotary disk electrodes of different number of teeth.

60 The use of the spark gap stabilizer serves also to render the note sharper and smoother, and from the tests made in practical embodiments of the invention, there appears to be a distinct action of the stabilizer electrode with the fixed and rotary electrode to increase the voltage gradient in the vicinity of the spark gap.

65 In Fig. 4, there is illustrated a practical

embodiment of a rotary spark gap provided with the stabilizer, the type of spark gap being any approved form, such as the type where the rotary disk electrode 60 is connected on the rotor shaft 82 of an inductor type alternator driven by an airfan, usually at a constant speed.

70 In such type of rotary spark gap, the stationary electrode is indicated at 83 and the stabilizer electrode at 84, shown mounted with the opposite end clips 85, 86, snapped onto the opposite posts 87, 88, respectively.

75 In the particular electrode disk 60 shown in Figs. 4 and 5, the number of teeth is twelve. The disk is provided with the keyway 89 corresponding to the key on the rotor shaft 82 and the disk electrode 60 is located thereon by means of the nut 90.

80 By reason of the stabilizing effect of the stabilizer electrode, the output of the power transformer is increased and the radiation is increased, and the efficiency of the component parts of the entire transmitting set is also increased.

85 Whereas I have described the invention 90 by reference to specific forms thereof, it will be understood that many changes and modifications may be made without departing from the spirit of the invention, as defined by the appended claims.

95 I claim:

100 1. The combination with a source of continuous, alternating currents, of a tuned circuit including a fixed electrode and a rotary electrode, means operating said rotary electrode in synchronism with said source, and a member of electrically conducting material disposed laterally of the path of rotation of said rotary electrode.

105 2. The combination with a source of continuous, alternating currents, of a tuned circuit including a fixed electrode and a rotary electrode, means operating said rotary electrode in synchronism with said source, a member of electrically conducting material disposed laterally of the path of rotation of said rotary electrode, and means connecting said electrically conducting material with ground.

110 3. The combination with a source of continuous, alternating currents, of a tuned circuit including a rotary electrode and a fixed electrode disposed substantially in the plane of rotation of said rotary electrode, a member of electrically conducting material disposed a fixed distance laterally from the path of rotation of said rotary electrode and means operating said rotary electrode in synchronism with said source.

115 4. The combination with a source of continuous, alternating currents, of a tuned circuit including a rotary electrode and a fixed electrode disposed substantially in the plane of rotation of said rotary electrode, a member of electrically conducting material dis-

posed a fixed distance laterally from the path of rotation of said rotary electrode and means connecting said member with ground.

5. The combination with a source of continuous, alternating currents, of a tuned circuit including a fixed electrode and a rotary electrode, means operating said rotary electrode in synchronism with said source, and a

member of electrically conducting material disposed laterally of the path of rotation of said rotary electrode and adjacent said fixed electrode.

In witness whereof I affix my signature.

HARRIET S. SULLIVAN,
Administratrix of the Estate of Walter M.
Sullivan, Deceased.
